UNITED STATES PATENT OFFICE.

WADE H. BLEVINS, OF PORTLAND, AND EARL S. BURDICK, OF MILWAUKIE, OREGON.

GOLF GAME.

Application filed March 5, 1924. Serial No. 697,031.

To all whom it may concern:

Be it hereby known that we, WADE H. BLEVINS and EARL S. BURDICK, citizens of the United States, and residents of, respectively, Portland, county of Multnomah, and State of Oregon, and Milwaukie, county of Clackamas, and State of Oregon, have invented a new and useful Golf Game, of which the following is a specification.

10 This invention relates more particularly to games for amusement and instruction.

An object of our invention is the construction of an exceedingly simple and highly entertaining game following closely after the 15 game of golf, but on a greatly reduced scale, in which the ball is kept in play by a mechanical manikin whose activities are controlled by the judgment of the player.

A further object is to instruct the players 20 in aiming or directing their shots, in judgment of distances and rules of golf in general.

A still further object is to enable one to 25 become proficient in the technique of golf at a small expense in the way of time and money.

These, and other objects, will become more 30 apparent by a study of the specification following, which includes the drawings in

Figure 1 is a plan of a golf course of which Figure 2 is a section along the line 2-2 in Figure 1 showing the contour of the land and the general construction of the 35 game, with the supporting legs cut away. Figure 3 is a front elevation of the manikin employed at a somewhat enlarged scale, when compared with Figures 1 and 2. The actual height of the manikin is in the neighborhood of five inches. Figure 4 is a side elevation of Figure 3 with a portion of the body broken away in section to show its 40 interior construction which permits the swinging of the body above the waistline on an axis approximately that of the player when making a stroke. Figure 5 is a front elevation of the manikin at the completion 45 of a stroke. Figure 6 is a side elevation of Figure 5. Figure 7 is a section along the line 7-7 in Figure 4 showing the body held in its extreme position by the stop member. Figure 8 is a section through the hands of

the manikin which consists of a chuck for holding different kinds of golf clubs.

Similar numbers of reference refer to the 55 same parts throughout the several views.

Referring more particularly to the drawings, we have illustrated our device in the form of a table consisting of a supporting top 10 on the legs 11 which may be folded 60 or adjusted if desired (means for folding and adjustment not illustrated, as they may be any of those means now common in the art). A ledge or wall 12 is formed around the outside boundaries of the course, whose surface 13 is preferably uneven and broken by a stream 14, hills 15, and other desirable 65 irregularities easily produced in papier-mâché or similar materials. This is preferably covered with flock to simulate grass. The areas 16 around the holes, which number from 1 to 9 inclusive, are preferably flat and light in color. A bunker 17 is also provided. In place of the regular golf ball 70 we have provided a light and somewhat irregular papier-mâché ball 18, also preferably light in color.

The manikin 19, itself, consists of two parts one of which includes the legs 20 which are adapted to set firmly on the surface of the course, and a rotatable body 21 having an inclined bearing 22 which receives the pivot 23 which is tapped into the inclined face 24 of the member 20. A torsion spring 25 slips over the bearing 22 and 80 its lower end passes through a hole in the bottom 26 of the member 21. On the upper end of the pivot 23 is secured a collar 27 by means of the pin 28 through which is passed the upper end of the spring 25. A 85 stop 28^A is provided on the inside of the manikin to engage the projecting pin 28 at the extremes of rotation of the member 21. The back 29 of the member 21 is preferably 90 made removable along the center line for the purpose of assembling and construction. No means for securing same is shown as this may be accomplished in any of the ways now well known in similar arts.

Rigid arms 30 terminate in a chuck 31 100 which is adapted to receive a variety of golf clubs 32, which are flattened at their upper ends 33 to insure their insertion in the chuck in one way only, and that is the way in

which they will be employed during play. It will be understood that the club is adjustable longitudinally. The knurled chuck 31 tightly holds or easily releases the golf club 32 under the control of the player.

The operation of the manikin is as follows: The ball 18 is presumably in place on the course and the manikin 19 is placed in position with relation to the ball, as shown in Figure 3, very much in the manner in which the player would stand if actually on the golf links. The player takes hold of the manikin's feet with one hand, and his head or other part of the member 21, with the other hand, and rotates the member 21 so that the spring 25 increases in tension, which amount he learns by experience and applies by judgment according to the position of the manikin and the kind of stroke he wishes to make. When he has turned the member 21 sufficiently, in his judgment, for the purpose intended he releases same permitting the member 21 to swing around on its pivot causing the club 32 to strike the ball 18. The rules of the game of golf are followed throughout as far as practicable.

It will be understood that the details of the game may be modified greatly to correspond with the amount of money it is desired to expend upon the game. For instance, the links themselves may be on a perfectly flat board, such as heavy cardboard, and folded to a convenient size, and instead of using the ball 18 a disk or other substitute for a ball may be employed, without departing from the spirit of our invention. The manikin itself may be varied as to its construction and operating mechanism, and in some special cases it might be found desirable to provide definite points at which it could be set before releasing same. However, it is thought that for the purpose of cultivating judgment rather than mere skill, or the production of high scores, that it is preferable to provide a manikin along the lines illustrated in the drawings.

We are aware that different types of golf games have been constructed in the past, we therefore intend to cover only such golf

games as include mechanically operated 50 players under the control of the human players.

We claim:

1. A manikin golf player comprising ground-engaging legs cut off on a slope at 55 the waist line; a forwardly leaning pivot projecting perpendicularly from said sloping surface; a trunk rotatably mounted on said pivot; a stop in said trunk adapted to limit the follow through movement of said 60 trunk; a spring in said trunk adapted to urge same into the position of the completed stroke; and a golf club held by the arms of said trunk.

2. A manikin golf player having ground- 65 engaging leg members cut off at the waist line on a forwardly sloping plane; a pivot projecting perpendicularly from said sloping plane; a hollow trunk mounted on said pivot, said trunk having a closed lower end 70 and having a hub formed on the upper side of said lower end adapted to rotate on said pivot; a spring on said hub secured to a pin in said pivot and to said lower end of the trunk; a stop on the inside of said trunk 75 engaging said pin when the trunk has rotated an amount equal to that required to make a stroke at golf; and an adjustable golf club held in a chuck by said manikin.

3. A manikin golf player consisting of 80 ground-engaging lower limbs; an inclined pivot projecting from said lower limbs; a trunk rotatably mounted on said pivot; a torsion spring between said trunk and legs; and a plurality of interchangeable golf clubs 85 adapted to be manipulated by said trunk.

4. A manikin golf player consisting of 90 ground-engaging legs, said legs sloping towards the front at the waistline; an inclined trunk pivotally mounted on the sloping top of said legs; a stop for preventing the complete rotation of said trunk on said legs; spring means for urging said trunk in one direction; and a golf club removably held in relation to said trunk.

WADE H. BLEVINS.
EARL S. BURDICK.
